SEWING MACHINE

Herbert E. Althens, Newton, Mass., assignor to
 The Reece Button Hole Machine Company,
 Boston, Mass., a corporation of Maine

Application December 24, 1943, Serial No. 515,538

4 Claims. (Cl. 112—219)

This invention relates to the starting and stopping and work clamping mechanism of sewing machines, and the present application is a continuation in part of an application filed January 8, 1943, Serial No. 471,642.

An example of a type of machine to which the present invention is applicable is the button sewing machine described in the patent to Reece No. 2,158,199, May 16, 1939, wherein are employed a work clamping presser foot which is manually operated or lifted (as by a treadle) to release the work, together with power control or stop mechanism which is separately manually operated (as by a second treadle) to start the machine and automatically operated to stop the machine upon the completion of a predetermined sewing operation. However, the invention is equally applicable, at least in part, to other types of sewing machines having separately operated work clamp releasing and starting and stopping devices.

In machines of this general type, it is highly desirable (in order to avoid injury to the needle or the work or both) that the operator be prevented from releasing or lifting the work clamping devices except when the machine is at rest, or about to stop, and with the needle free from the work, and also be prevented from starting the machine unless the work is properly clamped. Various expedients, in the nature of interlocks between the manually operated work clamping and releasing and starting and stopping devices, designed to accomplish these results, have been proposed, but so far as I am aware none of these have been such as to prevent manual release or lifting of the work clamp during the final stitch-forming cycle of the sewing operation. In all machines of which I am aware, to which such prior expedients have been applied, the power control or stop mechanism is of such a character, and must be so timed, as to move into stopping position just after the beginning of the final stitch-forming cycle, during which the needle descends to penetrate the work and thereafter withdraws therefrom. Consequently, should the operator attempt to anticipate the stopping of the machine, by pressing upon the work clamp releasing treadle prior to the completion of the sewing operation (as frequently occurs), the interlock would be released and the work clamp lifted when the needle was descending or was engaged with the work. The present invention has for an object to provide a power control mechanism which is so constructed and timed, and is so inter-related or interlocked with the clamp releasing devices as to prevent release of

the work until after the needle has withdrawn from the work in the completion of the last stitch-forming cycle. The invention also has for an object the provision of an improved and simplified interlock for this purpose.

The foregoing and other objects of the invention, together with means whereby the latter may be carried into effect, will best be understood from the following description of an illustrative embodiment thereof shown in the accompanying drawings, this, however, having been chosen for purposes of exemplification merely, as it is contemplated that the invention, as defined by the claims hereunto appended, may be otherwise embodied without departure from its spirit and scope.

In said drawings:

Fig. 1 is a side elevation, partly broken away and partly in longitudinal section, of a button sewing machine including an embodiment of the invention, some parts of the machine not pertinent to the invention and not necessary to a full understanding thereof being omitted.

Fig. 2 is a horizontal section taken substantially on the line 2—2, Fig. 1.

Fig. 3 is a fragmentary horizontal section taken substantially on the line 3—3, Fig. 1.

Fig. 4 is a fragmentary vertical section taken substantially on the line 4—4, Fig. 2.

Fig. 5 is a view, similar to Fig. 4, showing certain of the parts of the latter figure in a different position.

Fig. 6 is a fragmentary side elevation of parts of the interlocking mechanism shown in Fig. 1, showing said parts in a different position.

Fig. 7 is a detail view of one member of the interlocking mechanism.

Figs. 8, 9, 10 and 11 are diagrammatic views illustrating the operation.

The invention is herein illustrated as embodied in a button sewing machine similar to that described in the aforesaid Reece patent to which reference may be had for a more complete showing of parts not fully shown and described herein.

Referring to Fig. 1, the frame or casing of the machine, which encloses the principal parts of the operating and controlling devices, comprises a base or bed 20 and an overhanging head 21 supported therefrom by an upright housing portion 22. The bed 20 carries a work plate 23 upon which is supported the work W to which a button B is to be attached and against which said work is clamped during the sewing operation by a presser-foot 24 associated with a button clamp

assembly A for holding and positioning said button.

The main driving and controlling instrumentalities include a main power or needle shaft 25 (see also Fig. 2) journalled in suitable bearings in the head 21 and to which power may be applied through a belt pulley 26 under the control of stop mechanism hereinafter described; and a cam shaft 27 journalled in suitable bearings in the casing, driven through a worm 28 and worm gear 29 from the needle shaft 25, and carrying a main cam 30.

The sewing instrumentalities include a needle 36 carried by a needle bar 37 guided for vertical movement in the head 21 and longitudinally reciprocated therein, to cause the needle to alternately penetrate the work and withdraw therefrom, by a crank 38 on the forward end of the needle shaft 25 and connected with said needle bar by a link 39. Within the bed 20 are suitable under thread handling devices or loopers (not shown) which cooperate with the needle in the formation of stitches.

Specifically, and except as it enters into combination with other parts hereinafter described, the button clamp assembly A with its presser foot 24 forms no part of the present invention and may be of any construction and arrangement suitable to perform its intended function. Said assembly includes a stem 46 carried by an arm 48 projecting from a slide 47 guided for vertical movement in the head 21. The slide 47 is normally pressed downwardly, to urge the presser foot 24 into clamping engagement with work W on the work plate 23, by a spring 48 but may be lifted or moved upwardly, against the tension of said spring, to release the work, by a lever 49 having a forked forward end 50 embracing a stud 51 projecting from the slide 47. Pivoted to the machine casing at 59 is a latch lever 52 (hereinafter more fully described) one arm 53 of which is connected by a link 54 with the lever 49. The upper end of the link 54 is formed with a slot 55 which receives a pin 56 projecting from the lever 49, and said link and pin are connected by a spring 58, this arrangement providing a variable yielding connection between the link 54 and lever 49 which permits the presser foot, under the influence of the spring 48, to accommodate itself to varying thicknesses of work. The arm 53 of the lever 52 is also connected by a link 57 with a treadle 58 or equivalent manually operated member.

Referring to Figs. 1 to 5, the belt pulley 26 is loose on the shaft 25 and is adapted to be clutched thereto by a combined clutch and stop device which as herein shown is similar to those shown and described in the patents to Mello, No. 1,227,643, May 29, 1917, and Reece, No. 1,730,014, October 1, 1929. Said device comprises a ring 64 carried by the pulley 26 and having a pin 65 which projects through a slot 66 in said pulley and is engaged by a spring 67 located in a recess in the pulley whereby said ring is permitted a yielding angular movement with respect to the pulley to cushion the shock of starting. The ring 64 has a shoulder 68 adapted to be engaged by a clutch dog 69 pivoted at 70 to a hub 71 keyed to the shaft 25 and normally urged into engagement with said shoulder by a spring 72 connecting said dog with an arm 73 fixed to said hub. The dog 69 is formed with a stop finger 74 adapted, when the connected parts are rotated in the direction of the arrows on Figs. 4 and 5, to engage a head 75 yieldingly mounted by means of

5 a spring 76 in the end of a stop arm 77 when the latter is in the position shown in broken lines in Fig. 1, thereby disengaging the dog 69 from the shoulder 68, as shown in Fig. 5, and stopping the rotation of the shaft 25, the shock of stopping being cushioned by the spring 76. Recoil of the shaft under the influence of the spring 76 is prevented by a pawl 78 normally urged into a position to be engaged by a shoulder 79 on the hub 71 by means of a spring 80. The stop arm 77 is formed with a cam surface 81 which cooperates with a plunger 82 slidably mounted in the frame and engaging the pawl 78. The arrangement of the parts is such that when the stop arm 77 is in the position shown in Fig. 2 and in full lines in Fig. 1, the head 75 is out of the path of movement of the finger 74 of the dog 69, permitting the latter, under the influence of the spring 72, to engage the shoulder 68, as shown in Fig. 4, thereby connecting the pulley 26 and hub 71 for rotation in unison in the direction of the arrows. The cam surface 81 at the same time acts through the plunger 82 to hold the pawl 78 in the inoperative position shown in Fig. 4. When the stop arm 77 is in the position shown in broken lines in Fig. 1, the head 75 will be engaged by the stop finger 74 to disconnect the parts and stop the machine, as above described. The cam surface 81 at this time permits the plunger 82 to be forced back by the spring 80, thereby permitting said spring to move the pawl 78 into operative position for engagement by the shoulder 79, as shown in Fig. 5.

The stop arm 77 is secured, as by a set screw 35 83 (Figs. 3 and 4), to a rock shaft 84 journalled in the casing and having secured thereto outside the casing an operating arm 85 (Figs. 1 and 2) connected by a link 86 with a treadle 87 (Fig. 1) or equivalent manually operated member. To start the machine, the treadle 87 is depressed, thereby rocking the shaft 84 in the direction to move the stop arm 77 into the position shown in full lines in Fig. 1. The machine having been started will continue to operate until automatically stopped. For this purpose the following mechanism is provided:

Secured to the rock shaft 84 is an arm 91 (Figs. 1, 3 and 4) having a bifurcated end between the bifurcations of which is pivoted a bunter 92 having a bevelled free end 93 (Fig. 3) adapted to be engaged by a stud 94 projecting from the under side of the main cam 30 when the latter reaches a certain angular position hereinafter referred to. The bunter 92 is supported in a position in which its end 93 is in the path of movement of the stud 94 by a stud 95 suitably supported from the casing wall. Engagement of the end 93 of the bunter 92 by the stud 94 causes said bunter to be forced toward the left in Figs. 1 and 3, thereby rocking the shaft 84 in the direction to move the stop arm 77 into the position shown in broken lines in Fig. 1, in which its head 75 is in the path of movement of the stop finger 74 of the dog 69, to stop the machine as above explained. The stud 94 is preferably notched, as indicated at 96 in Figs. 3 and 11, so that the slight overthrow of the parts incidental to stopping the machine will bring the notch opposite the end of the bunter to permit the machine to be again started by operation of the treadle, as in the Reece Patent No. 2,158,199, above referred to. The stop arm may be yieldingly retained in stopping or running position by engagement of a spring pressed positioning plunger 97 (Figs. 2 and 3), carried by the arm 85, with

suitably positioned recesses in the wall of the casing.

The shaft 27 of the main cam 38 being connected with the needle shaft 25 by the worm gearing 28, 29, said main cam is rotated in definite time relation, and at a reduced speed, with respect to the needle shaft. The main cam makes one complete rotation during a plurality but predetermined number of complete rotations of the needle shaft, each corresponding to a stitch-forming cycle during which the needle descends to penetrate the work and thereafter rises therefrom. Consequently, there is a definite portion of the angular movement of the main cam corresponding to each stitch-forming cycle, and the stud 94 is so positioned, with respect to the portion of angular movement (indicated at *a* in Fig. 3) corresponding to the final stitch-forming cycle of the complete predetermined sewing operation, as to engage and operate the bunter 82 just prior to the completion of said final stitch-forming cycle. Also, the dog 69 is so angularly positioned on the hub 71, and consequently on the shaft 25, with respect to the angular positioning of the crank 38 (or equivalent needle bar actuating means) on said shaft, that the stop finger 74 approaches the plane of movement of the head 75 of the stop arm 77 (as shown in Fig. 4), and engages said head to stop the machine (as shown in Fig. 5), if the stop arm is in stopping position, just prior to the completion of each stitch-forming cycle and after the needle has risen or been withdrawn from the work.

The relative timing of the parts is diagrammatically illustrated in Figs. 8 to 11. In Fig. 8, the final stitch-forming cycle has been a little more than half completed; the needle 36 is in the work W, has reached its lowermost position, and has started to rise therefrom; the stud 94 has not yet engaged the bunter 82, so that the stop arm 77 is still in running position with its head 75 out of the path of movement of the stop finger 74; and the dog 69 is engaged with the shoulder 68, thereby coupling the pulley 26 to the needle shaft 25. In Fig. 9, the needle has risen far enough to disengage or be withdrawn from the work but is still in proximity thereto, the stud 94 has been brought into engagement with the inclined end 93 of the bunter but has not yet moved the latter, so that the stop arm is still in running position and the pulley 26 remains coupled to the needle shaft. In Fig. 10, the needle, now completely withdrawn from the work, is approaching its uppermost position, the stud 94 has moved the bunter 82 far enough to swing the stop arm 77 into stopping position with its head 75 in the path of movement of the stop finger 74 which has reached an angular position where it is about to engage said head. In Fig. 11, the needle has reached its uppermost position remote from the work, and the stop finger 74 has engaged the head of the stop arm, thereby disengaging the dog 69 from the shoulder 68, uncoupling the pulley 26 from the needle shaft and positively stopping the latter. It will therefore be seen that the stop arm (together with the rock shaft 84 and arm 85) remains in running position until the needle has been completely withdrawn from the work at substantially the completion of the final stitch-forming cycle, and that when the stop arm is then moved into stopping position the machine is almost immediately stopped with the needle still remote from the work.

In order to prevent lifting of the presser-foot 24, by the treadle 58, to release the work, except

when the machine is at rest, or is about to stop, with the needle disengaged from the work, and to prevent movement of the stop arm 77 into running position, by the treadle 58, to start the machine, except when the work is properly clamped to the work plate by the presser-foot, the interlock mechanism best shown in Figs. 1, 2, 6 and 7 is provided. The latch lever 52, whose pivot 59 is directly below the free end of the operating arm 85 to which the link 86 is attached, is in the form of a bell crank lever having, in addition to the arm 53, a second arm 101 which extends upwardly toward the arm 85. The arm 101 is formed with an upper arcuate edge portion 102 concentric with the axis of the pivot 59 and underlying a pin 103 extending laterally from the arm 85, said edge portion terminating in a notch 104 adapted to receive said pin. Turning of the lever 52 on its pivot 59 in a counter-clockwise direction, under the influence of the springs 48 and 60, is limited by engagement of the arm 101 with a pin 105 projecting from the casing wall, and when said arm is in engagement with said pin in the notch 104 is directly opposite the pin 103. Otherwise, the arcuate edge portion 102 is of sufficient length to underlie the pin 103 throughout the range of lifting movement of the presser-foot by the treadle 58.

When the machine is at rest, with the stop arm 77 and operating arm 85 in the stopping position shown in broken lines in Fig. 1, the pin 103 is free from the notch 104, and the presser-foot 24 can be lifted by depression of the treadle 58. When this is done, the arcuate edge 102 of the arm 101 of the latch lever 52 passes under the pin 103, as shown in Fig. 6, thereby blocking downward movement of the arm 85. Consequently, so long as the presser-foot remains lifted, and the work is unclamped, the arm 85 cannot be operated by the treadle 58 to move the stop arm 77 into running position, shown in full lines in Fig. 1. When the treadle 58 is released, permitting the spring 48 to restore the presser-foot to work-clamping position, the latch lever 52 moves into the position shown in Fig. 1, carrying the arcuate edge 102 out of blocking relation to the pin 103 and bringing the notch 104 opposite said pin. The treadle 58 can then be freely depressed to move the stop arm into running position, shown in full lines in Fig. 1, to start the machine. When this is done, the pin 103 enters the notch 104, thereby locking the lever 52 against clockwise movement and preventing depression of the treadle 58 to lift the presser-foot and release the work. This condition exists so long as the stop arm is in running position and until it is moved into stopping position, shown in broken lines in Fig. 1, to stop the machine. As above explained, this does not occur until the final stitch-forming cycle has been nearly completed and the needle fully retracted from the work. Consequently, should the operator attempt to anticipate the stopping of the machine by exerting pressure on the treadle 58, this would not result in lifting the presser-foot until after the needle has been fully retracted from the work in the completion of the final stitch-forming cycle, after which the machine is almost immediately stopped, so that the needle cannot again descend into engagement with the work.

I claim:

1. In a sewing machine having work clamping means, in combination, manually operated means for starting said machine, other manually operated means for releasing said clamping means,

and means for preventing the concurrent operation of said manually operated means comprising a pivotally mounted latch having a notched arm adapted to prevent the operation of said starting means except when said notch is in position to receive an element of said starting means and having a lever arm connected with an element of said clamp releasing means, said arms having a relative position such that any movement of said lever arm in response to actuation by said releasing means serves to move said notched arm into a position in which said notch is thrown out of receiving position.

2. In a sewing machine having work clamping means, in combination, manually operated means for starting said machine, other manually operated means for releasing said clamping means, and means for preventing the concurrent operation of said manually operated means comprising a pivotally mounted latch having a notched arm associated with said starting means and a lever arm connected to an element of said releasing means, said notched arm being adapted to prevent said starting means from assuming starting position except when an element thereof is in line with said notch, the reception of said element into said notch acting to lock said latch against pivotal movement and thereby to prevent operation of said releasing means while said starting means is in operation.

3. In a sewing machine having work clamping means, in combination, manually operated means for starting said machine, other manually operated means for releasing said clamping means, and means for preventing the concurrent operation of said manually operated means comprising a pivotally mounted latch having one arm

with an arcuate edge concentric with the axis of said latch adapted to maintain a constant predetermined distance between said axis and an element associated with said starting means, a notch formed in said edge adapted to receive said element so as to permit said starting means to assume starting position, and a second arm connected to an element of said releasing means adapted on the operation of said means to turn said latch to move said notch out of receiving position and to move said arcuate edge into a position opposite the element associated with the starting means so that said starting means is locked in inoperative position during the operation of said releasing means.

4. In a sewing machine having work clamping means, in combination, manually operated means for starting said machine, other manually operated means for releasing the clamping means, and means for preventing the concurrent operation of both manually operated means comprising a pivotally mounted latch having one arm with an arcuate edge concentric with the axis of the latch adapted to maintain a constant predetermined distance between the axis and an element associated with the starting means, a notch formed in said edge adapted to receive said element when the starting means is in starting position, and a second arm connected to a member of the releasing means, the reception of the element of said starting means into the notch acting to lock the latch against pivotal movement so that the second arm connected to an element of the releasing means prevents the operation of said means.

HERBERT E. ALTHENS.
